UNITED STATES PATENT OFFICE.

JAMES W. HOOP, OF HUNTINGDON, PENNSYLVANIA.

DESIGN FOR A POKER.

SPECIFICATION forming part of Design No. 20,142, dated September 9, 1890.

Application filed August 5, 1890. Serial No. 361,147. Term of patent 7 years.

To all whom it may concern:

Be it known that I, JAMES W. HOOP, a citizen of the United States, residing at Huntingdon, in the county of Huntingdon and State of Pennsylvania, have invented and produced a new and original Design for Pokers, of which the following is a specification, reference being had to the accompanying drawings, forming part thereof.

- 10 In said drawings my design is shown in side elevation, and the leading feature consists in a stove-lid lifter *a*, which extends down from the body *b* of the poker between the point *c* and handle *d*. The lifter *a* is secured to a straight body portion *b* by a pair of arms *e*, which converge into one as they extend downward, thereby leaving a triangular opening *f*. The one arm *a*, which forms the lifter, curves gracefully forward toward
- 15 the point *c* of the poker in the arc of a circle. Upon the end of the main part of the lifter there is a chisel-shaped head *g*, having a smaller curve which intersects that of the lifter.
- 20

The handle *d* consists of a frame *i*, which is encircled by rings *j*, symmetrically spaced to present an ornamental appearance. The frame *i* is secured to a socket *k*, within which the end of the poker fits, and the outer end of the frame is provided with a knob *m*, forming a graceful termination for the handle.

What I claim is—

The herein-described design for a poker, the same comprising a straight portion, an open-work handle, a curved portion connected to the straight portion by converging arms, and a flat head forming an extension of said curved portion, but made on a curve intersecting that of the latter, as shown.

In testimony whereof I affix my signature in the presence of two witnesses.

JAMES W. HOOP.
